FURNACE GRATE

Filed Feb. 18, 1932

WITNESS.

Robt. R. Stetzel.

FIG. 2. John J. Fleming

Augustus B. Strongton
ATTORNEY.

UNITED STATES PATENT OFFICE

JOHN J. FLEMING, OF VINELAND, NEW JERSEY

FURNACE GRATE

Application filed February 18, 1932. Serial No. 593,730.

The subject of my invention is an improved furnace grate especially adapted to burn buckwheat coal under natural or chimney draft. My improved grate permits of substantially complete combustion of the fuel, because it insures an adequate supply and distribution of air both from beneath to the fuel on the grate and to the space directly above the fuel on the grate. By supplying air to the space above the fuel on the grate a satisfactory combustion of the gases distilled from the coal is obtained. My improved grate also permits thorough removal of ash and avoidance of clinker by providing teeth at the edge of the grate which grind the clinker and which provide a space through which the ash may escape.

In general my grate consists of a support, a bottom member carried by said support and having an outer annular portion, a perforated conical grate carried on said bottom member, and a flue extending through and above said conical grate for conducting air to the space above the fuel on the grate.

For a further exposition of my invention reference may be had to the annexed drawing and specification at the end whereof my invention will be specifically pointed out and claimed.

In the drawing,

Figure 1 is a central vertical cross section through my device.

Figure 2 is a plan view with parts broken away on the line 2—2 of Figure 1.

In that embodiment of my invention chosen for illustration in the drawing, my device is shown as consisting of a support 1 which may be a flange or shoulder on the wall of the furnace or other surrounding casing 2.

Mounted on support 1 I provide a bottom member which includes an outer annular member 4 which has a plurality of openings 5 therein. Openings 5 are of decreasing cross section from the top to the bottom to retain coals which lodge therein until they are completely burned. On its outer upper edge, outer member 4 is provided with upstanding teeth 6 which provide notches or openings 7 between them. Across one diameter of the bottom member extends a

bracket 8 having an enlarged central portion 9 which carries a groove 10 therein which serves as the lower race for a plurality of ball bearings 11. Bracket 8 also has a central opening therein. Depending from a portion of bracket 8 is a perforated lug 13 which is opposite to a similar perforated depending lug 14 on the outer portion 4.

A shaft 15 is mounted in the perforations in lugs 13 and 14 and carries at an intermediate portion a gear 16. At its outer end beyond furnace 2 shaft 15 has an end 17 suitable for receiving an actuating member such as a crank (not shown).

Mounted on portion 9 of bracket 8 on the ball bearings 11 there is provided a conical grate generally indicated at 18. Grate 18 has a central stub shaft 19 projecting through the hole in bracket 8. Opposite portion 9 of bracket 8 the grate has a bearing member which has an upper ball race therein for receiving the upper portion of ball bearings 11. In its sloping walls grate 18 has a plurality of side openings 20. Grate 18 is open throughout the lower portion of its bottom face and at its bottom outer edge carries a plurality of teeth 21 adapted to mesh with gear 16. On its outer lateral edge grate 18 carries a plurality of extending fingers 22 which extend opposite to teeth 6 of outer portion 4. Fingers 22 and teeth 6 support fuel thereon so that it is exposed to the draft through openings 5. Fingers 22 and teeth 6 also provide a cutting or grinding action for portions of ash or clinker which lodge therebetween.

In its central portion grate 18 has a tube 23 having a plurality of openings 24 in its side walls and an opening 25 at its top. Surrounding opening 25 on the top of grate 18 I provide a flue 26 which consists of an upstanding wall having a closed top 27. Adjacent the top of carburetor 26 there are provided a plurality of openings 28 which are preferably of V-shape so that the greater proportion of air is expelled from the tops of the holes and so that lodgement of fuel in the holes is very difficult.

It is believed that the operation of my device would be fairly obvious from the fore-

going description. Fuel such as buckwheat coal is placed within the furnace 2 upon the grate 18 and the bottom member. The level of the height of the fuel is preferably slightly below the openings 28 in carburetor 26. Air under natural, chimney or forced draft enters through openings 5 or through the bottom of grate 18 and openings 20 to the under side of the fuel bed whence it rises through the fuel bed and promotes an even and active combustion therein. Additional air passes through the bottom of grate 18, through the openings 24 and the openings 28 in flue 26. This air is delivered preferably to the space above the fuel bed and thereby promotes combustion of the gas which is distilled from the upper and relative cool portion of the fuel bed. As the fuel bed burns ash is formed on the bottom member and the lower parts of grate 18. Grate 18 may then be oscillated or rotated by means of gear 16 on shaft 15. This causes relative movement of fingers 22 and teeth 6. This movement causes a cutting or crushing action on any fuel or clinker which is lodged therebetween. Any fuel in this portion of the grate is readily burned due to the air supplied through openings 5 and between the edge of grate 18 and bottom member. Clinker or ash readily falls through the space between the lower part of grate 18 and the bottom member into an ash pit beneath the grate.

Although grate 18 and bottom member are shown as circular in plan they may, if desired, be made rectangular in outline in plan. I may also provide other types of bearings than the ball bearings 11 if I so desire.

I do not intend to be limited in the practice of my invention save as the scope of the prior art and of the attached claim may require.

I claim:

A furnace grate intended for the complete combustion of coal including in combination a support, a bottom member mounted on said support and having a perforated outer portion, upstanding teeth on said outer portion, said perforations in said outer portion being of decreasing cross section from top to bottom, a bracket across said bottom member and having a central opening and a bearing race therein, a perforated depending lug on said bracket, a perforated depending lug on said outer portion, a shaft mounted in the perforations in said lugs, a gear mounted on said shaft, means for attaching an actuating member to said shaft, a conical perforated grate mounted on said bracket, a stub shaft on said grate extending through said central opening, rotatable bearings interposed between said bracket and said grate, teeth on the lower outer edge of said grate cooperating with said gear, outstanding fingers on the lower lateral edge of said grate spaced opposite said upstanding teeth on said outer

portion, a tube extending vertically centrally of said grate and having perforations in its lateral walls, a wall upstanding from said grate and surrounding the upper end of said tube, a solid top on said wall, and perforations in the upper portion of said wall adjacent said top.
